UNITED STATES PATENT OFFICE.

FRANK E. BURLEY, OF CHICAGO, ILLINOIS.

DESIGN FOR AN OYSTER-PLATE.

SPECIFICATION forming part of Design No. 31,886, dated November 28, 1899.

Application filed November 4, 1899. Serial No. 735,841. Term of patent 14 years.

To all whom it may concern:

Be it known that I, FRANK E. BURLEY, a citizen of the United States, residing at Chicago, in the county of Cook and State of Illinois, have invented and produced a new and original Design for Oyster-Plates, of which the following is a specification, reference being had to the accompanying drawings, forming a part hereof.

10 Figure 1 is a plan view of a plate, showing my new design; and Fig. 2, a sectional view taken on the line 2 2 of Fig. 1.

As shown in the drawings, the leading feature of my design consists of a body portion 15 A, having an annular rim B extending downwardly and at a pronounced angle to the main

body portion, the whole presenting, as shown in the drawings, a handsome and ornate appearance.

Having described my invention, what I claim as new, and desire to secure by Letters Patent, is—

The design for an oyster-plate, as herein shown and described.

In testimony whereof I have signed my name to this specification in the presence of two subscribing witnesses.

FRANK E. BURLEY.

Witnesses:

THOMAS F. SHERIDAN,
THOMAS B. MCGREGOR.
